UNITED STATES PATENT OFFICE.

THOMAS CARTER, OF BELTON, SOUTH CAROLINA.

FIREPLACE HEATER AND COOKER.

1,352,048.

Specification of Letters Patent.

Patented Sept. 7, 1920.

Application filed May 3, 1918. Serial No. 232,333.

To all whom it may concern:

Be it known that I, THOMAS CARTER, a citizen of the United States, residing at Belton, in the county of Anderson and State of South Carolina, have invented new and useful Improvements in Fireplace Heaters and Cookers, of which the following is a specification.

This invention relates to a novel and improved heater and cooker for fireplaces of that kind in which an open grate is disposed within the fireplace for the purpose of heating a room or apartment within which the front of the fireplace is arranged.

One object of my invention is to provide a device comprising a drum or oven which is set within the fireplace and so arranged as to be heated by the bed of fuel in the grate and by the products of combustion passing to the chimney flue, so that the drum may be utilized as an oven for cooking purposes or for heating air for passage therethrough into one or more rooms to be heated, thus preventing waste of heat and securing a conservation of fuel and enabling one or more rooms, additional to the room in which the grate is arranged, to be heated from the same source of heat.

Another object is to provide a drum of which one end wall forms the back of the grate and whose top wall lies in the path of the products of combustion flowing to the chimney, whereby the interior of said drum will be effectually heated for the purposes described.

Another object is to provide a baffle plate disposed above the top of the drum to form therewith a primary flue or passage for the products of combustion, whereby such products will be caused to flow in direct contact with the top of the drum and the baffle plate to effectually heat the same, the said baffle plate being provided with pot holes or otherwise suitably constructed or arranged to also serve as a hot plate for cooking purposes.

Another object is to provide a drum which is set in an inclined position for co-operation with the baffle plate to cause the downward deflection of the products of combustion without impairing the draft.

Another object is to provide a drum having an open end which faces the room at the opposite or at a different side of the fireplace from the room in which the grate is

arranged, said open end being provided with a door which may be employed for controlling the supply of heated air to the first-named room and which adapts the drum to be used as an oven for cooking purposes. 60

With these and other objects in view, the invention consists of the features of construction, combination and arrangement of parts, hereinafter fully described and claimed, reference being had to the accompanying drawing, in which:—

Figure 1 is a vertical front-to-rear section through a fireplace, showing the heater and cooker arranged therein.

Fig. 2 is a vertical transverse section on the line 2—2 of Fig. 1.

Fig. 3 is a view in elevation looking toward the back of the fireplace.

Fig. 4 is a horizontal section through the fireplace and heater and cooker, showing a modified construction and arrangement of the heater and cooker. 75

Fig. 5 is a diagrammatic plan view showing another form of construction of the heater and cooker. 80

Fig. 6 is a vertical transverse section on the line 6—6 of Fig. 4.

Fig. 7 is a vertical transverse section on the line 7—7 of Fig. 6.

Fig. 8 is a vertical transverse section on the line 8—8 of Fig. 5, and

Fig. 9 is a vertical transverse section on the line 9—9 of Fig. 5.

Referring now more particularly to Figs. 1, 2 and 3 of the drawing, 1 designates a fireplace, which may be of any ordinary or preferred construction, and of any of the forms or types in general use, properly modified, when required, for the application of the invention. This fireplace is provided with the chimney flue 2 and in the front portion thereof is formed the fore portion or jamb 3 in which the open grate 4 is arranged. The fireplace, as shown in Figs. 1, 2 and 3, may be of that type of construction in which a single grate is disposed in the front portion of the fireplace facing a single room, or of that construction in which grates are arranged at opposite sides, or at front and rear of the fireplace, facing two opposite rooms, as in a two-room heating construction. 100

In carrying my invention into practice I provide a combined heater and cooker comprising a drum 5, made of cast iron, sheet 110

metal or other suitable material or materials. This drum consists of a box-like casing, preferably of rectangular or oblong rectangular form, and which is properly disposed in the base of the fireplace 1. As shown, the fireplace is provided with an opening which extends through and from the front 6 thereof to and through the rear 7 thereof, it being understood that the front 10 6 of the fireplace may extend into or face one room or apartment, while the rear 7 of the fireplace forms a partition wall between such room or apartment and an adjacent room or apartment of a house or 15 other structure.

The drum 5 comprises a suitable base or bottom wall 8, an end wall 9, side walls 10, and a top wall 11. The bottom wall 8 is suitably supported upon the base of the 20 fireplace, and the end wall 9 is arranged to form the back of the grate 4. The top wall 11 terminates below the arch 12 of the fireplace opening, so as to provide an intervening channel or passage 13 for the upward 25 and rearward flow of the products of combustion from the grate to the chimney flue 2.

For the purpose of deflecting the products of combustion downward into contact with the top wall 11, on the travel of such 30 products through the passage 13, a baffle plate 14 is provided. This baffle plate is supported from the wall 11 by suitable upright bracket pieces 15, and is so disposed as to cause the products of combustion flowing upwardly from the grate into the passage 13 to be thrown downwardly against the top wall 11 before their passage into the flue 2, thus effecting the heating of the top of the drum 5 to a high degree. It will 35 be evident from the foregoing description that the wall 9 of the drum will be heated by the body of fuel in the grate, while the wall 11 will be heated by the traveling products of combustion, so that a large portion 40 of the heat ordinarily allowed to go to waste will be utilized to heat the interior of the drum.

For the purpose of enabling the products of combustion to be deflected downwardly 50 into contact with the wall 11, without impairing the draft, the drum 5 is properly set in an inclined position, so that its top wall 11 will incline upwardly and rearwardly to a sufficient extent to allow the products to flow upwardly as they approach the flue 2. For convenience of construction, both the bottom wall 8 and the top wall 11 are arranged in an inclined position, so that said walls may be disposed in parallelism, but 55 it will of course be understood that the bottom wall may be horizontal and that the top wall 11 only need be inclined.

The deflector or baffle plate 14 is also designed to serve the function of a hot plate 60 for cooking and similar purposes, to which

end it is provided with one or more openings or pot holes 16, so that cooking utensils or the like resting upon the plate may be heated by direct contact with the products of combustion below. In order to enable this deflector or baffle plate to be properly disposed for the purposes described, a chamber or opening 17 is cut out or formed in the brick work or material of which the fireplace is formed, and an opening 18 is also formed 70 by cutting away the rear portion of the arch 12, in which opening 18 the plate 14 is disposed so as to separate the passage 13 from the opening or chamber 17. The opening or chamber 17 may extend out either at the 75 front or one side of the fireplace, as desired and as may be most feasible in different forms of fireplaces, and forms a supplemental overhead oven to receive the utensils containing the food or the like to be cooked, 80 and provides also for the proper application of the same to and removal of the same from the plate 14.

The front end of the drum 5 terminates flush with the rear surface 7 of the fireplace 90 and is preferably open and adapted to be closed by a hinged door 19, which may be secured in closed position in any suitable manner and which is preferably provided with a knob or handle 20 whereby it may be 95 conveniently manipulated. The portion of the surface or wall 7 forming the rear side of the flue 2 is preferably cut away some distance above the top 11 of the drum 5, providing a heating chamber 21 at the base 100 of the flue. This chamber 21 is closed on its outer side by a plate 22, which may be integral with or secured to the top 11 of the drum 5, and which serves as a conductor for the radiation of heat from said chamber 21. 105

In practice, it will be understood that the room or apartment in which the grate 4 is arranged at the front or one side of the fireplace will be heated directly from the fire in the grate, while the air contained within 110 the drum will be heated in the manner described. By opening the door 19 to a greater or less extent this heated air may be allowed to pass out of the open front end of the drum into the room or apartment at the rear 115 or opposite side of the fireplace, whereby both rooms will be simultaneously heated from the same source of heat, thus insuring a conservation of fuel, as the second room will be heated from the waste heat ordinarily allowed to discharge through the chimney. It will, of course, be understood that the door 19 may be provided with a register, or outlet opening closed by a slide or the like, so that a desired amount of heated air may be allowed to pass from the drum into the second room to be heated without the necessity of opening the door. It will, 120 of course, be understood that such second room will also be heated by radiation of heat 125 130

from the chamber 21 through the plate 22, thus further conserving fuel, and in addition the room in which the grate is arranged will be heated by the heat from the supplemental oven or chamber 17, whereby a very large part of all of the available heat units from the body of fuel within the grate will be utilized for heating purposes.

In practice the drum 5 may also be employed as an oven for cooking purposes, to which end it may be provided upon the interior thereof with flanges or ledges 23 to support sliding shelves or the like 24, on which food or vessels containing the same may be placed for baking and similar cooking operations. It will thus be seen, therefore, that the device is not only adapted to be used for heating an additional room from the waste heat from the grate, but also serves as an efficient type of cooking stove, or as a warming oven, forming a great article of convenience to householders or roomers in cases where economy in the use of fuel is a factor of importance.

The construction shown in Figs. 1, 2 and 3 is adapted for efficient use for heating adjoining rooms on opposite sides of a wall or partition, wherein the fireplace is formed as a part of such wall and projects at the front into one of the rooms, in addition to its described capabilities of use as a cooker. It will, of course, be understood, however, that by running additional pipes or flues out from the side of the drum 5, and providing the same with suitable dampers, the heat from the drum may also be conducted to other portions of either of the rooms or to still other rooms of a building, so that one or more additional rooms may be heated to a desired greater or less extent.

In Fig. 4 I have shown an adaptation in which the drum 5 is of the same construction as above described, but is arranged in a different manner in the fireplace 1. In this construction the drum 5^a is placed in a position at right angles to that shown in Figs. 1, 2 and 3, or in a direction transversely of the fireplace 1. By this arrangement one of the sides 10 of the drum forms the front wall of the drum and the back of the grate 4, while the opposite side 10 of the drum forms the back wall thereof and rests against the back wall 7 of the fireplace 1 which is closed throughout. The open end of the drum in this construction projects outwardly through one side of the fireplace, thus providing a supplemental heater and cooker for the room or apartment in which the grate is arranged. It will be evident that with this form the room or apartment on the opposite side of the wall 7 is not intended to be heated, the object in this case being to provide a combined heater and cooker, with an open grate fireplace, for a single room. The dotted lines 25 shown in this figure are designed

to indicate that, within the scope of the invention and range of use, the drum 5^a may extend through the rear wall 7, for use as indicated in Figs. 1, 2 and 3, or may be extended either through the side of the fireplace especially illustrated in Fig. 4 or through the opposite side.

In Fig. 5 I have shown an arrangement wherein the fireplace 1^a is arranged at the corner intersection of three adjoining rooms which the wall surfaces 26, 27 and 28 respectively face. In one of these wall surfaces, as the wall surface 26, the fireplace opening is formed to receive the grate 4^a and drum 5^b, and from said opening extend other openings 29 and 30 which lead outward through the other wall surfaces 27 and 28. In these openings 29 and 30 are placed auxiliary drums 5^c and 5^d which communicate at their inner ends with the drum 5^b and are provided at their outer ends with doors 19^a similar to the door 19. With this construction one of the rooms will be heated by the grate, while the air in the drums 5^b, 5^c and 5^d will be heated by the bed of fuel on the grate and the escaping products of combustion, the heated air being employed to heat the other two rooms. Any number of adjoining rooms, from two to four, may be directly heated in this manner according to the arrangement of rooms and fireplace of any particular floor or story of a building, and if desired flues, provided with suitable dampers, may lead to other rooms to be heated, such as the rooms of an upper floor. It is to be understood that the drums 5^c and 5^d may also serve as ovens for cooking purposes as previously described in connection with the construction shown in Figs. 1, 2 and 3.

My invention also contemplates the use of the heater and cooker in the upper floors of a building, in which case the construction will be the same as previously described, except that the drum or drums may also extend into the flue 2 so that the upper drum or drums will also be heated by the products of combustion flowing through the chimney from the lower grate or grates. Of course in this case the upper drum or drums will be so placed in the flues that they will not obstruct the draft.

It is to be understood, of course, that the grates may be designed for the use of coal, wood or other fuel, and that the construction and arrangement will vary within certain limits according to variations in the construction and arrangement of fireplaces and chimneys in different dwellings or other buildings. In all cases, however, the described general characteristics of the invention will be preserved, although it is to be understood that, while the device is particularly designed for use as a combined heater and cooker, it may be employed for

heating purposes alone where the user does not desire to employ it for cooking purposes.

The main characteristic of my invention is that it provides for economy and conservation in the use of fuel, in utilizing heat ordinarily allowed to go to waste and in providing means whereby one or more additional rooms may be heated from a single grate fire, and whereby the room in which the grate is arranged will also be better heated. Economy, convenience and manifold advantages are also gained by the adaptation of the device as a cooker and warming oven, thus reducing the number of fires to be kept up and amount of fuel consumed. Also where two grates in adjoining rooms are employed, it will be seen that the invention allows one of these grates to be dispensed with and both rooms to be heated from a single grate with great economy.

Having thus fully described my invention, I claim:—

1. In a device of the class described, a wall having an opening therein extending from one face to the other thereof and an oven chamber above the opening, a flue above the opening and communicating with the latter, a casing in said opening, the said casing having one end arranged flush with one face of the wall and its opposite end spaced inwardly from the other face of the wall, the last mentioned end of said casing having a grate, a plate closing the bottom of said oven chamber and disposed above the

top of said casing and forming a flame passage therewith, and the said flame passage communicating with the said flue.

2. In a device of the class described, a wall having an opening extending from one face to the other thereof and having an oven chamber above the opening, a casing in said opening with one side flush with one face of said wall, the said wall having a flue therein disposed near the said wall face and communicating with the top of said casing, a plate on another side of said casing and covering a portion of said flue, a plate closing the bottom of said oven chamber and forming a flame passage with the top of said casing, the said flame passage communicating at one end with said flue and being narrower at the said end than at its opposite end, and a grate on one face of said casing.

3. In a device of the class described, a wall having an opening therein extending from one of its faces to another thereof and an oven chamber above the opening, the said wall having a flue therein and communicating with said opening, a casing in said opening and having one of its walls arranged flush with one face of said wall and another of its walls spaced inwardly from the other face of said wall, a plate closing the bottom of said oven chamber and forming a flame passage above said casing and in communication with said flue, and a grate on one wall of said casing.

In testimony whereof I affix my signature.
THOMAS CARTER.
